UNITED STATES PATENT OFFICE.

EDWARD CORNWALL GORDON, OF NEW YORK, N. Y.

DESIGN FOR A TREAD FOR TIRES.

• 57,040.

Specification for Design.

Patented Feb. 1, 1921.

Application filed April 13, 1920. Serial No. 373,564. Term of patent 3½ years.

To all whom it may concern:

Be it known that I, EDWARD CORNWALL GORDON, a citizen of the United States, residing at #1935 Daly avenue, county of Bronx, city and State of New York, have invented a new, original, and ornamental Design for Treads for Tires, of which the following is a specification, reference being had to the accompanying drawing, forming part thereof.

Figure 1 is a plan view of the tread, showing my new design, and Fig. 2 is a transverse sectional view of the same, along line 2 of Fig. 1.

I claim:

The ornamental design for a tread for tires, as shown.

In testimony whereof, I affix my signature, this 6th day of April, A. D., 1920.

EDWARD CORNWALL GORDON.
